UNITED STATES PATENT OFFICE.

LEWIS KNOX, OF QUEEN JUNCTION, PENNSYLVANIA.

AUTOMATIC PIPE-WRENCH.

1,153,694.

Specification of Letters Patent. Patented Sept. 14, 1915.

Application filed February 27, 1915. Serial No. 11,034.

To all whom it may concern:

Be it known that I, LEWIS KNOX, a citizen of the United States, residing at Queen Junction, in the county of Butler and State 5 of Pennsylvania, have invented certain new and useful Improvements in Automatic Pipe-Wrenches, of which the following is a specification.

The present invention relates to certain 10 new and useful improvements in wrenches, and has for its object to provide a pipe wrench which embodies novel features of construction whereby it can be readily applied to a pipe and then manipulated in the 15 necessary manner for screwing the pipe into or out of position without the necessity for releasing the grip upon the pipe and taking a fresh grip thereon each time the handle is reciprocated back and forth.

20 Further objects of the invention are to provide a pipe wrench of this character which is comparatively simple and inexpensive in its construction, which can be quickly applied to a pipe and manipulated 25 in the usual manner, which will enable a pipe to be screwed into or out of position without mutilating the same, and which comprises few and durable parts such as are not liable to get out of repair and will successfully withstand the hard usage to which 30 such tools are ordinarily subjected.

With these and other objects in view, the invention consists in certain novel combinations and arrangements of the parts as will 35 more fully appear as the description proceeds, the novel features thereof being pointed out in the appended claims.

For a full understanding of the invention, reference is to be had to the following description and accompanying drawing, in which:

Figure 1 is a top plan view of a wrench constructed in accordance with the invention, showing the parts as assembled in the 45 positions assumed when operating upon a pipe or the like. Fig. 2 is a similar view showing the blocks removed from the ratchet wheel and the rings of the stock. Fig. 3 is a longitudinal sectional view on the line 3-3 of Fig. 1. Fig. 4 is a fragmentary view of one of the blocks applied to one of the rings of the stock, portions being broken away and shown in section. Fig. 5 is a transverse sectional view taken 50 on the line 5-5 of Fig. 4.

Corresponding and like parts are referred

to in the following description and indicated in all the views of the drawing by the same reference characters.

Specifically describing the present embodiment of the invention, the numeral 1 designates the handle or stock of the pipe wrench. One end of the handle is bifurcated, each arm of the bifurcation being in the form of a ring 2, said rings having corresponding openings in one side thereof and the said openings being normally closed by removable blocks 3. Any suitable form of latch means may be utilized for retaining the blocks in position within the openings. 60 In the present instance the blocks 3 are shown as provided at opposite ends thereof with slideable plungers 4 which are adapted to be projected into engagement with recesses 5 formed in the end walls of the side 65 openings of the rings 2. Springs 6 engage the latch bolts 4 and normally tend to project the same into operative position. The inner ends of the latch bolts 4 are offset from each other and loosely connected to 70 opposite ends of a transverse lever 7 which is pivoted at an intermediate point upon a pivot bolt 8, one end of the said bolt projecting from the top of the block 3 and terminating in a suitable handle or finger 75 piece 9. The springs 6 normally hold the latch bolts 4 in a projected position, although by turning the handle 9 and swinging the transverse lever 7 the two latch bolts 4 can be simultaneously withdrawn 80 into inoperative position for the purpose of placing the block 3 into position or removing it therefrom.

A ratchet wheel 10 is journaled between the arms of the bifurcated end of the stock 85 1. The periphery of the wheel 10 is provided with ratchet teeth 11 adapted to be engaged by a pawl 12 arranged at the base of the bifurcation of the stock and pivotally mounted upon the pin 13. Any suitable 90 spring 14 may be provided for holding the pawl 12 normally in a yielding engagement with the peripheral teeth 11 of the ratchet wheel 10. The ratchet wheel 10 is provided with a central opening 15 having a pair of 100 oppositely disposed curved end walls 15^a which are concentric with the center of the wheel and a pair of opposed straight walls 15^b. Extending around the central opening 15 on each side of the ratchet wheel 10 is an 105 outwardly projecting hub portion or boss 16, said bosses being received within the re- 110

spective rings 2 so as to rotate therein and provide a bearing for the ratchet wheel.

One side of the ratchet wheel 10 is provided with an opening which is normally filled by a removable block 17 and which corresponds to the before mentioned side openings of the rings 2. The outer end of the block is provided with ratchet teeth 17^a corresponding with the ratchet teeth 11 of the wheel 10, while the inner end of the block normally extends flush with one of the straight or flat sides 15^b of the opening 15 so as to close the said opening. In order to hold the block 17 removably in position a pair of sliding latch bolts 18 are provided in opposite sides thereof. Springs 19 engage these latch bolts and normally force them into a projected position. The outer ends of the latch bolts are adapted to engage recesses 20 in the walls of the side opening of the ratchet wheel, while the inner ends thereof are offset from each other and pivotally connected to opposite ends of a transverse lever 21 which is mounted at an intermediate point in its length upon a pivot bolt 22, one end of the bolt projecting beyond the block where it is provided with a finger piece 23. With this construction it will be obvious that by turning the finger piece 23 and swinging the transverse lever 21 the latch bolts 18 can be withdrawn for the purpose of placing the block in position or removing it therefrom, although as soon as the finger piece is released the latch bolts will be again projected outwardly into operative position by the action of the springs 19.

The opening 15 of the ratchet wheel 10 is provided with a pair of opposed jaws 24, the rear faces of the jaws being curved in a manner to correspond with the curved sides 15^a of the opening 15, while the outer faces of the jaws are substantially straight and provided with the teeth 25. Projecting rearwardly from each of the jaws 24 is a stem 26 which is slidably received within a radial opening 27 of the ratchet wheel 10. These stems 26 are threaded and are engaged by nuts 28 which are seated within recesses or slots formed in the wheel 10 and intersecting the radial openings 27. With this construction it will be obvious that by rotating the nuts 28 the jaws 24 can be bodily moved inwardly and outwardly so as to be brought closer together or moved farther apart, as may be necessary to grip the particular piece of pipe being operated upon. The sides of the nuts 28 project slightly beyond the faces of the ratchet wheel 10 and may be provided with small projections 29 so that they can be readily engaged by the fingers for the purpose of rotating the nuts to adjust the jaws.

In the operation of the pipe wrench, the block 17 of the ratchet wheel 10 and the two blocks 3 of the rings 2 are removed prepara-

tory to applying the tool to the pipe. When the wheel 10 is rotated to bring the radial opening thereof into registry with the side openings of the rings 2, a pipe can be moved through the openings into the central opening 15 of the ratchet wheel. The blocks 3 and 17 are then replaced and the jaws 24 moved inwardly so as to grip the pipe. By reciprocating the handle 1 the ratchet wheel 10 may then be rotated so as to screw the pipe either into or out of position, as may be desired. The jaws 24 retain their original grip upon the pipe until after the operation has been completed and it is desired to remove the wrench from the pipe, thereby preventing the mutilation of the pipe which is usually incident to the operation of those wrenches in which the jaws take a fresh grip upon the pipe each time the handle is reciprocated. The wrench can be quickly applied to or removed from a pipe and after the pipe has once been gripped thereby it can be readily rotated without danger of the jaws slipping upon and failing to grip the pipe.

Having thus described the invention, what I claim as new and desire to secure by Letters Patent, is:—

1. A ratchet wrench including a handle having a ring at one end thereof, said ring being formed with a side opening through which a pipe or the like can be inserted, a ratchet wheel journaled upon the ring and formed with a central opening, said ratchet wheel being also provided with a side opening corresponding to the side opening of the ring and adapted to be brought into registry therewith, a block fitted removably within the side opening, a spring pawl mounted upon the handle for engagement with the ratchet wheel, and jaws mounted upon the ratchet wheel so as to act upon a pipe or like member in the central opening thereof.

2. A ratchet wrench including a handle having a ring at one end thereof, said ring being formed with a side opening, a ratchet wheel journaled upon the ring and formed with a central opening, said ratchet wheel being also provided with a side opening corresponding to the side opening of the ring and adapted to be rotated into registry therewith for the purpose of inserting a pipe or like member into the central opening of the ratchet wheel, jaws mounted upon the ratchet wheel for engagement with a pipe or like member in the central opening thereof, a block fitted removably within the side opening of the ratchet wheel, spring latch means for holding the block in position therein, and a pawl mounted upon the handle for engagement with the ratchet wheel.

3. A ratchet wrench including a handle having a ring at one end thereof, said ring being formed with a side opening, a ratchet

wheel journaled upon the ring and provided with a central opening, said ratchet wheel being also formed with a side opening corresponding to the side opening of the ring and adapted to be rotated into registry therewith for the purpose of moving a pipe into or out of the central opening of the ratchet wheel, a block fitted removably within the side opening of the ratchet wheel, 5 spring actuated latch bolts slidably mounted upon the block for engagement with the ratchet wheel to hold the block in position, means for simultaneously retracting the latch bolts to remove the block or replace it in position, jaws mounted upon the ratchet wheel for engagement with a pipe or like member in the central opening thereof, and a pawl mounted upon the handle for engagement with the ratchet wheel.

20 4. A ratchet wrench including a handle having a ring at one end thereof, said ring being formed with a side opening, a ratchet wheel journaled upon the ring and formed with a peripheral row of teeth, said ratchet wheel being provided with a central opening and also with a side opening adapted to be rotated into registry with the side opening of the ring for the purpose of moving a pipe into or out of the central opening of the 25 ratchet wheel, a block fitted removably within the side opening of the ratchet wheel and provided with teeth arranged to form a continuation of the teeth thereof, jaws mounted upon the ratchet wheel and arranged to grip a pipe or like member in the central opening thereof, and a pawl mounted upon the handle for engagement with the ratchet wheel.

5. A ratchet wrench including a handle 40 having a pair of spaced rings at one end thereof, said rings being formed with side openings, a ratchet wheel arranged between the rings and formed upon opposite sides thereof with hub portions which are journaled within the rings, said ratchet wheel being formed with a central opening and also with a side opening corresponding to the side openings of the rings and adapted to be rotated into registry therewith for the 45 purpose of moving a pipe or like member into or out of the central opening of the ratchet wheel, a block fitted removably within the side opening of the ratchet wheel, jaws mounted upon the ratchet wheel for engagement with a pipe or like member within the central opening thereof, and a pawl mounted upon the handle for engagement with the ratchet wheel.

6. A ratchet wrench including a handle 55 having a pair of spaced rings at one end thereof, said rings being formed with side openings, a ratchet wheel arranged between the rings and provided upon opposite sides thereof with hub portions which are journaled within the rings, said ratchet wheel

having a peripheral row of teeth and being formed with a central opening and a side opening adapted to be rotated into registry with the side openings of the rings for the purpose of moving a pipe or like member 70 into the central opening of the ratchet wheel, a block fitted within the side opening of the ratchet wheel and formed with teeth arranged to provide a continuation of the peripheral teeth of the ratchet wheel, latch 75 means for holding the block removably in position, jaws mounted upon the ratchet wheel to grip a pipe or like member in the central opening thereof, and a pawl mounted upon the handle for engagement with 80 the teeth of the ratchet wheel.

7. A ratchet wrench including a handle provided with a pair of spaced rings at one end thereof, said rings being formed with side openings, a ratchet wheel arranged between the rings and formed upon opposite sides thereof with hub portions which are journaled within the rings, said ratchet wheel having a peripheral row of teeth and being provided with a central opening and also 85 with a side opening adapted to be rotated into registry with the side openings of the rings to admit of a pipe or the like being moved into or out of the central opening of the ratchet wheel, a block fitted removably within the side opening of the ratchet wheel, latch means for retaining the block removably in position, said block being provided with teeth arranged to form a continuation of the teeth of the ratchet wheel, blocks 90 fitted removably within the side openings of the rings, latch means for retaining the said blocks in position, jaws mounted upon the ratchet wheel and arranged to grip a pipe or like member in the central opening 95 thereof, and a pawl mounted upon the handle for engagement with the ratchet wheel.

8. A ratchet wrench including a handle having a ring at one end thereof, said rings being formed with a side opening, a ratchet wheel journaled upon the ring and formed with a central opening and also with a side opening leading to the central opening and adapted to be rotated into engagement with 110 the side opening of the ring for the purpose of moving a pipe or like member into or out of the central opening of the ratchet wheel, jaws arranged upon opposite sides of the opening of the ratchet wheel, threaded stems projecting rearwardly from the jaws, nuts carried by the ratchet wheel and engaging the stems of the jaws to move the jaws in and out, a block fitted removably within the side opening of the ratchet wheel, 115 and a pawl mounted upon the handle for engagement with the ratchet wheel.

9. A ratchet wrench including a handle provided at one end thereof with a pair of spaced rings formed with corresponding side 120

openings, a ratchet wheel arranged between the spaced rings and provided upon opposite sides thereof with hub portions journaled within the rings, said ratchet wheel being formed with a central opening and also with a side opening leading to the central opening and adapted to be rotated into registry with the side openings of the rings to admit of a pipe or like member being moved into or out of the central opening of the ratchet wheel, jaws arranged upon opposite sides of the central opening of the ratchet wheel, threaded stems projecting rearwardly from the jaws, nuts carried by

the ratchet wheel and engaging the threaded stems to move the jaws toward and away from each other, a block fitted removably within the side opening of the ratchet wheel and provided with teeth forming a continuation of the teeth thereof, and a pawl mounted upon the handle for engagement with the ratchet wheel. 15
